DISPENSING DEVICE

Edgar W. Vahle, Dayton, Ohio, assignor to The Huffman Manufacturing Company, Dayton, Ohio, a corporation of Ohio

Application July 31, 1933, Serial No. 682,950

20 Claims. (Cl. 221—23)

This invention relates to liquid dispensers, and more particularly to devices for dispensing liquids, such as lubricating oil, enclosed in sealed containers.

5 Lubricating oil for automobiles is now being widely sold in sealed containers. Oil is so sold in order that the purchaser may be assured of receiving the quality and quantity of oil desired, free from adulteration, or contamination. 10 One of the principal objects of this invention is to provide a dispenser for sealed liquid containers, which is simple in construction and easy of handling and operation.

Another object is to provide such a dispenser 15 which is adapted for so dispensing the oil as to avoid any danger of contamination thereof.

Still another object is to provide such an oil dispenser which is adapted to receive the sealed container in telescopic relationship and in a pre- 20 determined positioning, and is provided with a member for piercing a discharge opening in the container through which the contents thereof are entirely discharged into the dispenser and out of contact with the container for delivery 25 from the dispenser.

Another object of the invention is to provide such a dispenser having a piercing knife so constructed that an opening is easily formed for discharging and venting the container, and 30 which is so formed that the pierced and empty container may be readily withdrawn from the container and the piercing knife.

Another object is to provide such a dispenser having a valved outlet and operating mechanism 35 therefor and means arranged to serve as a guard to protect the valve operating mechanism from injury by a container.

Other objects and advantages of the invention will be apparent from the following description, 40 the accompanying drawings and the appended claims.

In the drawings, in which like characters of reference designate like parts throughout the 45 several views thereof,—

Fig. 1 is a top plan view of the dispenser constructed in accordance with this invention;

Fig. 2 is a vertical section corresponding to the section line 2—2 of Fig. 1; a container being shown in dotted outline;

Fig. 3 is a plan view of the dispenser taken similarly to Fig. 1 and showing a container in position within the dispenser;

Fig. 4 is a fragmentary view in perspective of a portion of the valve operating mechanism and container guide;

Fig. 5 is a fragmentary plan view of the under- 55 side of the dispenser;

Fig. 6 is a sectional view taken on the line 6—6 of Fig. 5;

Fig. 7 is a fragmentary sectional view taken

on the line 7—7 of Fig. 2 looking down toward the cutting edge of the knife;

Fig. 8 is a plan view of the knife; and

Fig. 9 is a side elevational view of the knife with the knife supporting means shown in sec- 5 tion.

The drawings show a preferred embodiment of a dispenser containing the present invention. This dispenser comprises generally a cylindrical body 10 having a bottom 11 spaced some distance 10 from the lower edge of the body, that portion beneath the bottom forming a skirt 12 which serves as a support for the dispenser. The bottom 11 has a discharge opening located to one 15 side and preferably adjacent the wall of the dispenser body which is lowermost during discharge and the bottom itself preferably inclines downwardly toward this opening which therefore lies at the low point in the bottom. This discharge opening 13 in the bottom is controlled by means 20 of a valve 20 provided with suitable operating mechanism.

Attached to the lower side of the bottom 11 is a sheet metal plate 25, having an opening therein corresponding to the discharge opening 25 13 in the bottom. This sheet metal plate is provided with a downturned rim or flange 26 which receives the upper open edge 27 of the cup member 28, which member has a well portion designated by the numeral 29, having a discharge 30 opening in the vertical side wall 30 thereof. As shown particularly in Fig. 2 the cup member is provided with an inclined wall 32 which is located beneath the opening 13 so that oil discharging through the opening 13 will be directed 35 into the well 29 and out through the opening in the vertical wall 30 thereof.

Mounted within the opening in the vertical wall 30 is a ring member 35, which has a spherical 40 face 36, which cooperates with a complementary face 37 on the overturned end of a pouring spout 38, this construction permitting of ready swivel movement of the pouring spout during operation.

Opposite the cooperating spherical faces 36 and 37 the pouring spout is provided with a lug 40 45 having a passage 41 therein, one end of which opens into the interior of the pouring spout and the other end of which passage is bored out to provide a conical socket 43. This socket 43 receives a correspondingly tapered end portion 44 50 of the screw 45. The screw is threadedly mounted within a block or bushing 46 which is in turn carried within an opening in the plate 41. This plate 41 is attached to the wall of cup member 27 and also to the skirt portion to provide a rigid 55 support for the screw 45. By properly adjusting this screw, through turning thereof, the conical end portion is brought to bear upon the conical socket 43 to press the spherical faces 36 and 37 60 together to hold the spout so that it may be

readily swung about the axis of the spherical faces 36 and 37, which coincides with the axis of the screw 45, while at the same time sufficient frictional resistance is interposed to hold 5 the spout in any position in which it may be placed. The bushing 46 has its projecting end bifurcated, as shown particularly in Fig. 6, to receive a cotter-key 50 or other suitable locking member, for holding the screw 45 in adjusted 10 position. Inasmuch as the passage 41 opens into the discharge passage in the discharge spout, oil being dispensed may work in between the conical end 44 of the screw and the receiving socket 43 sufficiently to provide a self lubricated 15 bearing; and the same is true with respect to the spherical faces 36 and 37. Also by means of the adjusting screw 45 the spout may be held in proper swivel adjustment.

The valve 20 is carried at one end of a lever 20 arm 55, which is pivotally supported at 56, between two upstanding standards or brackets 57. As shown the brackets or standards 57 are spaced apart a distance substantially in excess of the width of the lever arm 55, and this lever arm 25 is supported upon a cotter-key which extends through suitable openings in the standards 57 and in the lever arm 55. The opposite end of the lever arm 55 is provided with a pivotal projection 58, which passes through a suitable opening 30 in the lower end of the operating link 59. This operating link passes upwardly through an opening 60 in the overturned flange 61 which is formed at the lower end of the can guiding and operating mechanism supporting member 62. 35 This member 62 is shown as formed of a metal stamping having a main body portion 63 which is curved throughout its main extent to correspond with the internal curvature of the body 10, and is preferably spotwelded to the inside of 40 that body portion with its top edge substantially flush with the top of the body 10. This portion 63, throughout a substantial part of its vertical height, has inwardly directed flanges 64, which are substantially parallel and each of 45 which has an overturned flange 65, which extends to contact with the inside of the body 10, the two flanges 65 lying in substantially the same vertical plane. The flange 61 is overturned at the bottom of the portion 63 and is substantially 50 horizontally arranged and extends inwardly towards the axis of the body 10. The link 59 throughout its lower portion is spaced a substantial distance inwardly from the wall of the body portion, but in its upper portion, is offset outwardly to lie closely adjacent the part 63, and completely contained within the space enclosed 55 between the flanges 64. The edges designated by the numeral 67 serve as spaced guiding and supporting portions for the can or container to 60 be inserted into the body of the dispenser, and the construction of these parts, and the location of these edges, is such that when the can or container is introduced into the body 10 the edges 67 will serve to guide and properly position it, and to definitely hold it in position where it cannot be brought into contact with the link 59 and other parts of the valve operating mechanism. The upper end of the link 59 is provided with an overturned tongue 70, which extends inwardly through an opening in the operating handle 71. This operating handle is shown as a substantially 90° bell-crank lever with the two arms thereof extending in planes substantially perpendicular to each other. The arm 72 which 70 has an opening therein for receiving the tongue

70 is also provided with a second opening through which is extended a cotter-key 73. The member 63 has a tongue portion 75 struck up therefrom as shown to serve as the internal support for the cotter-key and bell-crank lever, the outer end of 5 the cotter-key being supported in a suitable opening within the wall of the body portion 10, and adjacent the upper edge thereof. A spacing ring 76 also surrounds the cotter-key and is spaced between the inner wall of the body portion and 10 the arm 72 or operating handle, to provide a suitable positioning and mounting for the operating handle.

Preferably a handle 80 is attached to the body portion, this handle being so positioned that 15 when the handle is gripped in the hand of the operator the arm 81 of the bell-crank lever, which is arranged substantially radial to the body portion 10, is within easy reach to be moved by the thumb of the operator to open or close the valve 20 20. The link 59 has a portion 85 struck up thereon, beneath which is mounted a plate 86 which is slidable upon the link 59 and adapted to rest against a spring 87. A second plate 88 is also slidably mounted upon the link 59 and receives 25 the lower end of the spring 87. The plate 88 rests upon the upper face of the horizontally arranged flange 61. The opening 60 within the flange 61 is wider than the link 59 so that as the arm 81 is moved to swing the bell-crank lever and lift the 30 link 59 up and down to thus move the valve 20 toward and from its seat, the plate 88 may slide back and forth on the flange 61 to accommodate the travel of the link as the operating handle is moved. Also positioned upon the bottom 11 is 35 an upstanding bifurcated member 90, positioned to straddle the valve lever 55 and guide it as it moves up and down to open and close the valve. By means of the construction described the valve moves up and down so as to effectively seat upon 40 and close the opening 13, the link 59 tending to pivot around its point of connection with the lever 55, and thus impart no objectionable side-wise movement to the valve 20 as the opening and closing movement occurs. During this operation, 45 of course, the member 88 can slide on the flange 61 if necessary, and at extreme open position the bell-crank lever arm 72 and link have swung past center to hold the valve in open position. Reverse movement of the arm 81 causes the parts 50 to move so that the spring 87 moves the valve shut.

Attached to the body portion 10 opposite the member 63 is a plate 100 which is preferably spotwelded to the metal body 10. This plate 55 throughout its main body portion is of a curvature to correspond with the internal curvature of the body portion 10. This plate is preferably made as a metal stamping, and its outer or vertical edges are preferably struck inwardly, as shown by 60 the numeral 101. Supported upon this plate 100 is a knife, designated generally by the numeral 105, for piercing the end of the can or container, the contents of which are to be dispensed. As shown, the knife is formed from a piece of flat 65 steel stamped into substantially U-shape in cross-section, with the midportion 106 curved and of a radius corresponding to the radius of the cylindrical container the contents of which are to be dispensed. The plate is formed of stock which is 70 heavier than the metal of the body portion 10 and serves as a reinforcement and sufficiently substantial support for the knife. Because of this corresponding curvature this portion of the knife, when the container is inserted into the body 75

portion 10, will pierce the end of the container along a curved line lying immediately adjacent the curved edge of the can. The side members of the knife, 107, are slightly divergent with each other and are directed inwardly toward the axis of the body portion. The knife cutting edge is of generally V-shaped form with the apex along the longitudinal or vertical center of the curved portion 106 of the knife, and with the cutting edges 10 tapering downwardly throughout the extent of the curved portion and side members 107.

As the lubricant container is introduced into the body portion, the guiding member 67 will serve to properly position it within the body portion and bring the container against the opposite portion of the body with the curved portion 106 of the knife positioned to cut on a curve immediately within, and corresponding to, the curvature of the seam around the end of the can. 20 The telescoped container stands eccentrically with respect to the dispenser side wall. The spaced guide members are proportioned to accurately position the container on the diametral line extending from the side wall adjacent the knife 25 to intermediate the two guide members. This accurately locates the knife with respect to the container. The two guide portions 67 are shown as spaced apart a distance approximately the same as the container radius so that it will be apparent that their spacing is such as to permit 30 some movement of the container in a transverse direction so that it may be given a twisting movement sufficient to break the interengagement of the knife and the container. As the knife is 35 tapered the initial withdrawal movement is sufficient to free the container. As the can is pressed downwardly the apex of the knife first punctures the end of the can and as the can is moved downwardly the pouring opening is progressively cut, 40 and because of the downwardly inclined cutting edges, the cut out lip is simultaneously curled back and within the container.

In order to insure ready removal of the empty container, the knife is given a double taper so 45 that the size of the pouring opening is progressively increased throughout the full length of travel of the container during the cutting operation. As shown generally in Fig. 8 the side portions 107 flare outwardly or diverge downwardly 50 a slight amount from the top toward the bottom of the knife. Also the width of the side portions 107 increases from the termination of the cutting edge at the point 110 to a point 111 which marks approximately the point of maximum 55 downward travel of the container within the body portion. By so proportioning the knife the empty container is readily released therefrom upon withdrawal motion thereof. A slight twisting movement of the container facilitates initial dis- 60 engagement thereof. The knife is supported upon the member 100 by means of screws 115, which are threadedly mounted within the supporting plate 100 and within correspondingly threaded openings in the knife itself. By means 65 of this construction it is unnecessary to use nuts or other members that might come off during operation, and because of their small size, might travel out of the dispenser along with the oil into an automobile crank-case, to cause tremendous 70 damage to the automobile engine. The curved portion 106 of the knife, as shown, stands closely adjacent the side wall of the body portion 10, and the plate 100 serves as a stop to limit the downward travel of the container. This plate 100 is 75 so positioned that the space available in the

body portion 10 below the point of downward travel of the container or can, which is shown in dotted lines in Fig. 2, is sufficient in volumetric capacity to receive all of the oil or other liquid within the can without the upper surface of the 5 liquid coming in contact with the can. In this manner contamination of the oil by dirt or the like which might adhere to the can is prevented, and the clean oil just as it flows from the can or 10 container is dispensed through the spout. Further, the empty container when removed is not covered with oil.

The sealed containers from which the oil is discharged into the dispenser are generally made to an established liquid measure; consequently, 15 the dispenser need not be calibrated. It may, however, be provided with volume calibrations for use as a measure.

Because of the curvature of the portion 106 of the knife corresponding to the curvature of 20 the can, and the can having a diameter less than the diameter of the body portion 10, the curved portion of the knife would not exactly correspond in curvature with the body portion 10. The plate 100, with the struck up portions 101 along 25 its edges, thus provides a three point support for the knife, and by properly tightening the screws 115 the knife may be pulled down tightly and properly held against the plate 100 and the portions 101. 30

As shown, the spout is preferably a rigid tubular metal member, having its discharge end overturned somewhat and provided adjacent thereto with corrugations 120 which serve to engage the edge of the opening within the crank-case, or 35 other container into which the oil is to be discharged, to support the dispenser.

While the form of apparatus herein described constitutes a preferred embodiment of the invention, it is to be understood that the invention is 40 not limited to this precise form of apparatus, and that changes may be made therein without departing from the scope of the invention which is defined in the appended claims.

What is claimed is:

1. A liquid dispenser adapted to receive and open a sealed container and to dispense the contents thereof, having a side wall adapted to receive a container in telescopic relationship therewith, a container piercing knife positioned adjacent and in fixed relationship with the side wall, and container guide means extending axially of the dispenser and cooperatively related to the side wall and knife to position a container in predetermined relationship with respect to said knife, said guide means and said side wall providing three locating lines of engagement with the container two of which are substantially closer together than they are to the third. 45

2. A liquid dispenser adapted to receive and open a sealed container and to dispense the contents thereof, having a side wall adapted to receive a container in telescopic relationship therewith, a container piercing knife positioned adjacent and in fixed relationship with the side wall, and container guide means comprising a pair of parallel spaced guide members extending axially of the dispenser opposite said knife and cooperatively related to the side wall and knife to position a container in predetermined relation 65 with respect to said knife, the distance between said guide members being substantially the same as the container radius.

3. A liquid dispenser adapted to receive and open a sealed container and to dispense the con- 75

tents thereof, having a side wall adapted to receive a container in telescopic relationship therewith, a container piercing knife positioned adjacent and in fixed relationship with the side wall, and container guide means affixed to the dispenser side wall and angularly positioned with respect to said knife, said guide means comprising a unitary sheet metal part having parallel guide members extending axially of the dispenser and affording spaced contact points for the container which are cooperatively related to the side wall at the knife whereby the container is given a predetermined positioning with respect to said knife.

15. 4. A liquid dispenser adapted to receive and open a sealed container and to dispense the contents thereof, having a cylindrical side wall adapted to receive a container in telescopic relationship therewith, a container piercing knife positioned adjacent and in fixed relationship with the side wall, said knife having a curved blade spaced inwardly from the dispenser wall and having an upwardly projecting cutting edge, valve means for controlling the flow from the 25 container, and a pair of spaced container guide means opposite said knife and cooperatively related to the side wall and knife to eccentrically position a container so that the container side wall extends intermediate the knife and dispenser side wall during telescoping movement.

5. A liquid dispenser adapted to receive and open a sealed container and to dispense the contents thereof, having a side wall adapted to receive a container in telescopic relationship therewith, a container piercing knife positioned adjacent and in fixed relationship with the side wall, and container guide means comprising parallel spaced guide members extending axially of the dispenser and cooperatively related to the side wall and knife to position a container in predetermined relation with respect to said knife, said guide members being diametrically related with respect to said knife and extending inwardly from the dispenser side wall to position 40 a container eccentrically with respect to said side wall and being spaced with respect to the opposite side wall to position the container within close limits as regards the diametral spacing and the knife and to loosely receive the container in a direction perpendicular to the diametral line to afford lateral movement of the container sufficient to effect release of the container from the knife.

6. A liquid dispenser adapted to receive and open a sealed container and to dispense the contents thereof, having a side wall adapted to receive a container in telescopic relationship therewith and having a valved outlet, valve actuating means, a knife in said dispenser, a container 55 guide having spaced guide members to position a container in the dispenser in predetermined relationship with respect to said knife, supporting means within the dispenser for the valve actuating means, said guide members extending inwardly with respect to the valve actuating means and its support to form a guard to protect said means against contact by a container.

7. A liquid dispenser adapted to receive and open a sealed container and to dispense the contents thereof, having a side wall adapted to receive a container in telescopic relationship therewith and having a valved outlet, valve actuating means comprising a pivotally movable operating arm and a spring tensioned rod, a knife in said 70 dispenser, a container guide comprising a plate

attached to the side wall of the dispenser and having parallel inturned sides extending axially of the dispenser for guiding a container in predetermined relationship with respect to said knife, means on the container guide for supporting the valve operating arm and the spring tensioned rod thereon intermediate the inturned sides, said inturned sides extending inwardly of the dispenser side wall an amount sufficient to afford protection of the valve actuating parts from contact by a 10 container.

8. A liquid dispenser adapted to receive and open a sealed container and to dispense the contents thereof, having a side wall adapted to receive a container in telescopic relationship therewith and having a valved outlet, valve actuating means, a knife in said dispenser, and an integrally formed sheet metal member in said dispenser for guiding a container therein and for supporting the valve actuating means, said sheet metal 20 member comprising a plate shaped to conform to the contour of the dispenser side wall and adapted for surface engagement therewith, said plate having laterally spaced inwardly directed flanges extending axially of the dispenser and terminating 25 in overturned flanges which extend to the dispenser side wall, the lines of junction of each pair of flanges and the diametrically opposite side wall affording a three point container guide for positioning the path of movement of a container out 30 of the range of contact with the valve actuating means and in a predetermined relationship with respect to said knife.

9. A liquid dispenser adapted to receive and open a sealed container and to dispense the contents thereof, having a side wall adapted to receive a container in telescopic relationship therewith, a knife of substantially U-shape section within the confines of the side wall adapted to pierce the end of the telescoped container for 40 formation of a pouring opening therein, said knife having an upwardly pointing cutting edge and having the legs of the U section diverging downwardly with respect to one another whereby the pouring opening is increased as the telescoping 45 progresses to produce easy release of the container from engagement with the knife upon initial withdrawal movement of the container.

10. A liquid dispenser adapted to receive and open a sealed container and to dispense the contents thereof, having a side wall adapted to receive a container in telescopic relationship therewith, and a knife of substantially U-shape section in said dispenser having an upwardly projecting cutting edge adapted to pierce a pouring 55 opening in a container, said knife being of tapering shape increasing in width in one direction and in breadth in a different direction from the cutting edge whereby the pouring opening is increased as the telescoping progresses to produce 60 easy release of the container from engagement with the knife upon initial withdrawal movement of the container.

11. A liquid dispenser adapted to receive and open a sealed container and to dispense the contents thereof, having a side wall adapted to receive a container in telescopic relationship therewith, and a knife within the confines of the side wall and having an upwardly projecting cutting edge adapted to pierce a pouring opening in a 70 telescoped container, said knife comprising a curved portion spaced from the side wall and laterally inturned side portions extending inwardly from the side wall, said side portions diverging downwardly with respect to one another from the 75

top of the knife, the edges of the side portions being inclined from the top downwardly so that the side portions increase in width from the top downwardly, whereby the pouring opening increases as the telescoping of the container progresses to produce easy release of the container from engagement with the knife upon initial withdrawal movement of the container.

12. A liquid dispenser adapted to receive and open a sealed container and to dispense the contents thereof, having a cylindrical side wall adapted to receive the container in telescopic relationship therewith, a knife in said dispenser having an upwardly projecting cutting edge adapted to pierce a pouring opening in a container, said knife being formed from flat material to substantially U-shape, the curved midportion of said knife conforming substantially to the curvature of the side wall of the container the contents of which are to be dispensed and the in-turned side portions being flat, the knife having the top of its curved and side portions inclined downwardly from an apex located substantially upon the vertical axial line of the curved portion, the sides of the knife diverging downwardly a slight amount with respect to one another and the side inwardly presented edges being of gradually increasing width from the top toward the bottom of the knife, and means for supporting the knife in the dispenser spaced inwardly a distance somewhat greater than the seam surrounding the end wall of the container.

13. A liquid dispenser adapted to receive and open a sealed container and to dispense the contents thereof, having a side wall adapted to receive a container eccentrically in telescopic relationship therewith, a knife having a curved portion adapted to pierce a pouring opening in the container, knife supporting means comprising a plate curved to conform to the curvature of the side wall and having in-turned side edges affording spaced engagement with the knife, and clamping means for attaching the knife and plate to the side wall, said clamping means engaging the knife intermediate the spaced contact of the plate to provide a rigid three point support of the blade with respect to the plate.

14. A liquid dispenser adapted to receive and open a sealed container and to dispense the contents thereof, having a side wall adapted to receive a container in telescopic relationship therewith, a knife shaped with a smaller radius of curvature than said side wall to conform to the contour of the side of the container the contents of which are to be dispensed, knife supporting means comprising a plate attached to the side wall of the dispenser and having in-turned side edges extending axially of the dispenser and affording spaced parallel lines of contact with the knife, clamping means for the knife extending through the side wall and supporting member for engagement with the knife intermediate the spaced contacts of the supporting means and adapted to clamp the knife in tension to secure its positioning with respect to the supporting member and to hold the clamping means in engagement.

15. A liquid dispenser adapted to receive and open a sealed container and to dispense the contents thereof, having a side wall adapted to receive a container in telescopic relationship therewith, a knife shaped with a smaller radius of curvature than said side wall to conform to the contour of the side of the container, knife sup-

porting means comprising a plate attached to the side wall of the dispenser and shaped to conform to the contour thereof, said plate having in-turned side edges affording spaced parallel lines of contact, with the knife extending axially of the dispenser, knife attaching screws for holding the knife in clamped engagement on the side wall, said screws extending from the outside of the dispenser through the side wall and supporting means into threaded engagement with the knife and adapted upon being drawn tight to clamp the knife in tension whereby the knife is securely positioned with respect to the supporting means.

16. In a liquid dispenser having a discharge port and an interfitting and pivotally movable pouring spout in communication therewith, means for holding the pouring spout in fluid tight engagement with the discharge port comprising spout supporting means tensioned in surface engagement with said spout, said spout having a lubricant passage extending from the interior thereof to the spout surface at the place of engagement of the supporting means.

17. In a liquid dispenser having a discharge port and an interfitting and pivotally movable pouring spout in communication therewith, means for holding the pouring spout in fluid tight engagement with the discharge port comprising a tensioned member engageable with the pouring spout on the axis of rotation, and a passage extending from the interior of the pouring spout to the point of engagement of the tensioned member to afford lubrication thereto.

18. In a liquid dispenser having a discharge port and an interfitting and pivotally movable pouring spout in communication therewith, said parts having spherical interengaging surfaces, and means for maintaining said surfaces in fluid tight engagement comprising a conical socket formed in the pouring spout on the axis of rotation thereof with the apex toward the interengaging spherical surfaces, a conical pointed screw adapted to be received in said conical socket, means on the dispenser for supporting said screw in tensioned engagement with said socket, and a fluid passage extending from within the pouring spout to the conical socket affording a lubricant passage to the interengaging surfaces of the screw and conical socket.

19. In a liquid dispenser, a body having a discharge port and an interfitting and pivotally movable pouring spout in communication therewith, and an adjustable threaded member adjustably mounted on said body in line with the axis of rotation of said pouring spout and engaging said pouring spout to hold it against said discharge port and to center it pivotally on said body.

20. A liquid dispenser adapted to receive and open a sealed container and to dispense the contents thereof, having a side wall adapted to receive a container in telescopic relation therewith, a container piercing knife positioned adjacent and in fixed relationship with the side wall, and container guide means comprising a pair of parallel spaced guide members extending axially of the dispenser and cooperatively related to the side wall and knife so that the container is positioned by said pair of guide members and the side wall in predetermined relation with respect to said knife.

EDGAR W. VAHLE.
